VERTICAL OPPOSED CYLINDER INTERNAL
COMBUSTION ENGINE

John Lawrence Bogert, Brooklyn, N. Y.

Original application October 11, 1926, Serial No.
140,852. Divided and this application June 13,
1929. Serial No. 371,026

8 Claims. (Cl. 123—197)

My invention relates to improvements in vertical internal combustion engines where power-producing pistons reciprocate in a vertical or substantially vertical direction, in contradistinction to horizontal internal combustion engines where power-producing pistons reciprocate in a horizontal or substantially horizontal direction; and the objects of my improvements, first, an engine in which it is possible to have each individual connecting-rod transmit to its crank as much power while moving upward as while moving downward, thereby eliminating a serious difference in the torque developed by the same; second, increased power for a given length of engine; third, reduced bearing friction; and fourth, increased facility for the withdrawal of the pistons.

This application was originally a part of an application filed October 11, 1926, whose serial number is 140,852, and which application is now pending.

I attain the first of these objects by providing mechanism wherein and whereby all upward-acting power strokes shall exceed in force all downward-acting power strokes by an amount equal approximately to twice the power required to raise the weight of the reciprocating parts through the vertical height of their reciprocating paths. Thus if p' is the mean piston load during up-strokes, and p'' is the mean piston load during down-strokes, p' must exceed p'' by an amount equal to $2w$ where w is the pressure on a crank-pin due to the weight of all the parts that reciprocate up and down conjointly with the connecting-rod. Since if $p' - w$ equals p'' plus w , p' exceeds p'' by $2w$. It is obvious that since the force developed by the piston in any cylinder depends upon the product of the pressure by the area of the piston multiplied by the stroke, if the pressure and stroke remain constant the area acted on by the pressure during up strokes must exceed the area acted on by the pressure during down strokes.

I attain the second and third of my objects by employing a swinging beam construction which serves to transmit the upward thrust of a power-producing piston together with the downward thrust of a power-producing piston to the same crank-pin through a connecting-rod.

I attain the fourth of my objects by employing open end cylinders and trunk pistons in place of closed cylinders and double-acting pistons. So that, while my improved engines are true double-acting engines in which all power strokes, whether up or down, may be of equal

turning effect, no power-producing piston uses both its upper and its lower face in the development of power.

In a previous patent application 65,156, filed October 27th, 1925, for Improved internal combustion marine engines I have set forth and fully elucidated the prejudicial effect of the weight of the reciprocating parts in all vertical single-acting engines of the steam-hammer type, which prejudicial effect increases with the increase in the diameter of the pistons.

In the case of double-acting vertical internal-combustion engines of the steam-hammer type this prejudicial effect is so pronounced as to materially alter the stresses transmitted to the cranks on up and down strokes respectively. A double-acting 2-cycle vertical internal combustion engine of the steam hammer type whose output is as much as 700 to 800 horse-power per cylinder may transmit five times as much power to the crank-shaft during down strokes as during up strokes. It is evident that such engines are uneconomical from a structural point of view, since each crank of the crank-shaft must be strong enough to transmit the maximum stress to which it may be subjected, and economy of material will be secured by reducing all sources of fluctuating torque.

I claim broadly to be the first to discover and point out the important difference between the power transmitted to the cranks of a double-acting, vertical, steam-hammer type of engine during the up and down strokes, and to have pointed out in this patent application how to design and construct an engine in which, though vertical, no such inequality need exist.

I attain this desired end by means of the mechanism shown in the accompanying drawings. Similar numerals refer to similar parts in the several drawings.

Fig. 1 shows a vertical transverse sectional elevation of two opposed cylinders of a one or more crank engine unit embodying my improvements when the cylinders are slightly inclined to the vertical transversely, so that the center of gravity of the engine may be near to the vertical longitudinal plane through the axis of the crank-shaft.

Fig. 2 is a plan view that shows the swinging beam which is a fundamental part of my improved engine construction, and also a way in which the power producing cylinders may be attached to the framing and the same connected to the fulcrum shaft round which the beam swings up and down which the engine is in operation.

Figs. 3, 4, 5, 6 and 7 show detail views of the piston links and their connection with the pin by which they transmit motion to the swinging beam.

5 Fig. 8 shows a vertical longitudinal section thru the three cylinders of a vertical engine unit which comprises a modification of my usual construction in that the single lower cylinder is replaced by two cylinders whose pistons have the same combined area as the single piston which they replaced, which area may be twice that of the upper piston, but in any event should be sufficiently larger to overcome the disturbing effect of the weight of the reciprocating parts in rendering the power transmitted to the crank-shaft during up and down strokes unequal.

Fig. 9 is a plan view of the swinging beam.

Fig. 10 is a horizontal section through the ports of the upper single cylinder, while Fig. 11 is a horizontal section through the ports of the two lower cylinders.

1 is an upper cylinder, 2 an upper cylinder-head and 3 an upper piston. 4 is an upper piston link swivelling on a suitable wrist-pin attached to the upper piston 3, and swivellingly attached to a suitable pin 15 on the outer end of the swinging beam 13 whose function is to transmit the alternate up and down forces of its attached pistons to the crank-shaft thru a connecting-rod 17. 5 is a lower cylinder, 6 a lower cylinder-head and 7 a lower piston. 8 is a lower piston link swivelling on a suitable wrist-pin attached to the lower piston 7, and swivellingly attached to the above mentioned pin 15 on the out-end of swinging beam 13. 9 is a clamp which binds the bearing surfaces at the lower end of piston link 4 and at the upper end of piston link 8 to the swinging beam pin 15 round which they swivel. Figs. 3, 4, 5, 6 and 7 more clearly show the details of the mechanism by which the upper piston link 4 and the lower piston link 8 are swivellingly connected to swinging beam pin 15. Because pin 15 moves in a circular arc while pistons 3 and 7 move in a straight line, it is essential that provision be made for the swinging motion of the links 4 and 8 which transmit the thrusts of their respective pistons 3 and 7. The function of clamp 9 is to permit the slight swinging motion of these links which is necessary, while preventing any backlash or looseness of connection between pin 15 and the bearing surfaces formed on the ends of these links which engage with the same.

It is not absolutely necessary to use a single lower piston of larger diameter than the upper one, since two pistons below might be employed in twin open-end cylinders whose combined area exceeds the area of the upper piston by the desired amount. Fig. 8 shows this modification, and Figs. 9, 10 and 11 serve to make the necessary details of construction more clear.

12 is a tie-rod which connects the upper and lower cylinder or cylinders together in conjunction with framing 27. 13 is the swinging beam shown in the drawings constructed with right and left-hand members united together by means of pins 15 and 16 and stay 11. The spreading of the right and left hand members of swinging beam 13 where bearings 10 engage fulcrum shaft 14 is to prevent fore and aft motion of beam 13 when the ship is pitching at sea. Fulcrum shaft 14 is firmly secured at their junction to framing 23 and 26. Framing 23, 24 and 25 constitute a triangular structure which serves to bind the fulcrum shaft 14 to the upper end of the lower cylinder or cylinders and both these to the back of

bed-plate 22. Beam pin 16 carries connecting-rod 17 whose lower end engages with crank-pin 18 of crank-shaft 20. 27 is the framing that secures the lower cylinder or cylinders 5 to the bed-plate 22 and insures the alignment of the upper and lower cylinders. Framing 26 serves to tie the upper cylinder to fulcrum shaft 14. The drawings show engines fitted with 2-cycle cylinders, having the usual admission or scavenging ports as well as exhaust ports opening into the cylinders thru their liners, said ports being uncovered by the pistons during their outward movement near the end of their outward strokes. 28 is the upper exhaust manifold, 29 the lower exhaust manifold, 31 the scavenging air trunk for both upper and lower cylinders, 32 a branch pipe from the scavenging air trunk to the lower cylinder and 33 a branch pipe from the scavenging air trunk to the upper cylinder. 34 and 35 are supplemental or supercharging air trunks and 36 and 37 are the branch pipes through which this air passes to upper and lower cylinder-heads 2 and 6.

Many of the details that are well known and common to all internal combustion engines are omitted in the drawings to prevent complexity.

I claim:

1. A vertical opposed cylinder internal combustion engine in which the power producing pistons of single-acting 2-cycle cylinders reciprocate together in pairs in the same substantially vertical direction, the lower ones developing power during every up stroke and the upper ones during every down stroke, the lower pistons having the same stroke but greater area than the upper ones, in combination with mechanism for turning reciprocating motion into rotary motion substantially as represented and for the purpose set forth.

2. A vertical opposed cylinder internal combustion engine in which the power producing pistons of single-acting 2-cycle cylinders reciprocate together in pairs in the same substantially vertical direction, the lower ones developing power during every up-stroke and the upper ones during every down stroke, the lower pistons having greater area than the upper, the piston links of each pair of pistons swivellingly engaging with a common pin on a swinging beam which thru a connecting-rod which engages with a crank of a crank-shaft transmutes reciprocating motion into rotary motion, substantially as represented and for the purpose set forth.

3. A vertical opposed cylinder internal combustion engine in which power producing pistons reciprocate together in pairs in the same substantially vertical direction, the lower ones developing their power only during up strokes and the upper ones only during down strokes, the lower pistons having greater area than the upper ones, the piston links of both pistons of each pair being swivellingly connected to a common pin on a swinging beam which transmutes reciprocating motion into rotary motion thru a connecting rod which engages with a crank of a crank-shaft, substantially as represented and for the purpose set forth.

4. A vertical opposed cylinder internal combustion engine in which power producing pistons reciprocate together in pairs in the same substantially vertical direction, the lower ones developing their power only during up-strokes and the upper ones only during down strokes, the lower pistons having greater area than the upper ones, the outer ends of the piston links of each pair

- of pistons being swivellingly clamped together round a common pin on a swinging beam which transmutes reciprocating motion into rotary motion thru a connecting-rod which engages with 5 a crank of a crank-shaft substantially as represented and for the purpose set forth. 80
5. A vertical opposed cylinder internal combustion engine in which each upper cylinder is opposed from below by two cylinders, all three 10 of whose power producing pistons reciprocate together in a substantially vertical direction, the lower ones developing their power only during up-strokes and the upper only during down strokes, the two lower pistons in each set of three having 15 the same stroke as the upper one but jointly a greater area, in combination with mechanism for turning reciprocating motion into rotary motion substantially as represented and for the purpose set forth. 85
- 20 6. A vertical opposed cylinder internal combustion engine in which a single-acting 2-cycle cylinder is opposed from below by two single-acting 2-cycle cylinders, the pistons of all three cylinders reciprocating together in the same 25 substantially vertical direction, the lower ones developing their power only during up-strokes and the upper only during down strokes, the sum of the areas of the two lower pistons exceeding the area of the upper one, all three pistons being 30 swivellingly connected by links to a common pin on a swinging beam which transmutes reciprocating 35 into rotary motion thru a connecting-rod which engages with a crank of a crank-shaft substantially as represented and for the purpose set forth. 90
- 40 7. A vertical opposed cylinder internal combustion engine comprising an upper cylinder closed at its upper end by a suitable cylinder-head equipped with the necessary valves and valve-gear- 45 ing, and containing a reciprocating piston whose piston link is swivellingly attached to a pin carried on the outer end of a swinging beam which oscillates up and down round a fulcrum and transmits rotary motion to a crank-shaft 50 mounted in suitable bearings in a bed plate thru a connecting-rod, in combination with a pair of lower single-acting cylinders whose lower ends are closed by suitable cylinder-heads 55 equipped with the necessary valves and valve-gear- 55 ing, and containing reciprocating pistons whose piston links are swivellingly attached to the same outer pin on the outer end of said swinging beam, the sum of the areas of the two lower pistons exceeding the area of the upper 100 one, and all three pistons reciprocating together in the same substantially vertical direction, the whole mechanism being mounted on suitable framing attached to said bed-plate together with suitable mechanism for operating the various 105 valves and functional details substantially as represented and for the purpose set forth. 110
